(57) **CLAIM**

The ornamental design for a charging station as shown and described.

DESCRIPTION

FIG. 1 is a front perspective view of a charging station showing our new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The dash-dot-dash broken lines illustrate boundaries that form no part of the claimed design. The remaining broken lines depict features of the charging station that form no part of the claimed design.
